(57) **CLAIM**

The design for athletic pants with zippers, as shown and described.

DESCRIPTION

FIG. 1 is a front view of the athletic pants with zippers embodying my new design;

FIG. 2 is a right side view thereof, the left side being a mirror image of the right side view; and,

FIG. 3 is a rear view thereof.

The area of the waistband including vertical lines indicates the inclusion of elastic material, and the area of the waistband devoid of vertical lines indicates the inclusion of non-elastic material.
